[57] CLAIM

The ornamental design for a coin sorting mechanism, as shown.

DESCRIPTION

FIG. 1 is a bottom plan view of the coin sorting mechanism showing my new design;

FIG. 2 is a side perspective view of an open coin sorting mechanism of my new design;

FIG. 3 is a front perspective view of the mechanism; and

FIG. 4 is a rear perspective view.

The top and all sides are shown in the perspective views of FIGS. 3 and 4.

FIG. 1

FIG. 2

FIG. 3

FIG. 4
